(57) **CLAIM**

The ornamental design for a tool stand, as shown and described.

DESCRIPTION

FIG. 1 is an isometric view of a tool stand;

FIG. 2 is front view thereof;

FIG. 3 is a rear view thereof;

FIG. 4 is a left-hand side view thereof;

FIG. 5 is a right-hand side view thereof;

FIG. 6 is a top view thereof;

FIG. 7 is a bottom view thereof; and,

FIG. 8 is another isometric view of a tool stand showing a fastener mechanism as part of the environment for illustration.

The broken lines shown in the drawings illustrate the environment of the article and form no part of the claimed design.
